Christy M. Del Mas, New York, N. Y., assignor to Michael P. Grace, New York, N. Y.

Application December 12, 1952, Serial No. 22,683

Term of patent 14 years

(Cl. D44—1)

To all whom it may concern:

Be it known that I, Christy M. Del Mas, a citizen of the United States of America, residing at city, county, and State of New York, have invented a new, original, and ornamental Design for a Plaque, of which the following is a specification, reference being had to the accompanying drawing, forming part thereof.

The figure is a top plan view of a plaque, embodying my new design.

The plaque as to third dimension is a thin, flat plate-like device, plain on the side opposite that illustrated.

I claim:

The ornamental design for a plaque, as shown and described.

CHRISTY M. DEL MAS.
